BILLBOARD FRAME MOLDING

Filed Oct. 11, 1949

UNITED STATES PATENT OFFICE

2,603,014

BILLBOARD FRAME MOLDING

Pierre L. Michael, Houston, Tex.

Application October 11, 1949, Serial No. 120,687

2 Claims. (Cl. 40—125)

1

This invention relates to signboards, and more particularly to protective molding devices for billboard frames.

A main object of the invention is to provide a novel and improved protective and decorative molding for billboard frames and the like, said molding being very simple in construction, being easy to install, and serving to protect the frames of billboards against deterioration and decay.

A further object of the invention is to provide an improved sheathing for the frames of billboards, said sheathing providing a decorative molding for the frame, being inexpensive to manufacture, being neat in appearance, being rugged in construction, and greatly increasing the life of the billboard on which it is employed.

Further objects and advantages of the invention will become apparent from the following description and claims, and from the accompanying drawings, wherein:

Figure 1 is a front elevational view of a billboard provided with protective and decorative molding constructed in accordance with the present invention.

Figure 2 is an enlarged rear perspective view of the lower portion of the molding employed on the billboard of Figure 1, showing the joint construction employed to secure two overlapping sections of molding together;

Figure 3 is an enlarged fragmentary cross-sectional detail view taken on line 3—3 of Figure 1;

Figure 4 is an enlarged cross-sectional detail view taken on line 4—4 of Figure 1;

Figure 5 is an enlarged cross-sectional detail view taken on line 5—5 of Figure 1.

Referring to the drawings, 11 designates the main display backing plate of a billboard, said surface being of sheet metal or other suitable material. The billboard is of conventional construction and includes outer wooden frame elements 12 and inwardly-extending wooden molding elements 13 secured to the frame elements 12, the rectangular backing of sheet metal or other material employed for carrying the posters being secured to the rear surface of the molding elements 13, as shown in Figure 4.

The protective molding of the present invention is designated generally at 14. The molding 14 comprises elongated strips of suitable weather-resistant sheet metal, such as aluminum or the like, formed with a horizontal flange 15, as viewed in Figure 5, a vertical intermediate body portion 16, an inclined, inwardly-extending portion 17, and a V-shaped, inwardly-facing, marginal bead 18. As shown in Figure 5, the molding 14 is

2

adapted to be mounted in overlying relation to the outer frame elements 12 with the inner portion of the inclined section 17 abutting the lower corner of the molding section 13. The outer flange 15 is secured to the frame element 12 by means of nails 19, the portion of inclined section 17 abutting the corner of molding element 13 being likewise secured to the molding element 13 by similar nails 19. From Figure 5 it will be seen that the edge of the marginal bead 18 is spaced slightly from the backing plate 11. The strips are overlapped at their adjacent ends and are secured to the backing 11 at spaced locations by clip members, designated generally at 20, each clip member comprising a main body portion 21 secured to the section 17 at its end, as by rivet 22, and formed with an outwardly-bent arm 23 underlying and secured to the marginal portion of bead 18 by a rivet 24. Adjacent arm 23 the body 21 is formed with an apertured tab 25 which extends through a slot 26 formed in the backing plate 11, is bent rearwardly and upwardly along said backing plate, as shown in Figure 3, and is secured there to by a rivet 27. The clips 20 are employed at overlapping portions of the molding sections to fasten the inclined elements 17 of the sections together, as shown in Figure 4, by means of a rivet 28, the clips 20 being secured to the backing 11 in the same manner as described in connection with Figure 3.

At the corners of the billboard the molding sections 14 are formed with mitered, abutting edges, as shown at 29.

From the above description it will be seen that the molding sections provide a decorative and protective covering for the wooden frame elements of the billboard, whereby said frame elements are protected against deterioration and decay, and whereby the life of the billboard is greatly increased.

While a specific embodiment of a billboard frame molding has been disclosed in the foregoing description, it will be understood that various modifications within the spirit of the invention will occur to those skilled in the art. Therefore, it is intended that no limitations be placed on the invention except as defined by the scope of the appended claims.

What is claimed is:

1. In a billboard having a rectangular backing plate for supporting advertising material and a frame extending along the edges of and secured to said backing plate, a protective molding enclosing said frame and comprising elongated sheet metal strips disposed around said frame in

end to end relationship and each having along one edge a flange overlying and secured to the outer surface of the frame and a bead formation along its other edge disposed adjacent said backing plate inwardly of the frame, and clips secured to said strips at spaced apart locations therealong for securing said strips to said backing plate, said backing plate having slots therein disposed one adjacent each of said clips and each of said clips comprising a main body portion disposed at the frame adjacent side of the corresponding strip and secured to the latter and a tab extending from one end of said main body portion through the adjacent slot in said backing plate and secured to the latter.

2. In a billboard having a rectangular backing plate for supporting advertising material and a frame extending along the edges of and secured to said backing plate, a protective molding enclosing said frame and comprising elongated sheet metal strips disposed around said frame in end to end relationship and each having along one edge a flange overlying and secured to the outer surface of the frame and a bead formation along its inner edge disposed adjacent said backing

plate inwardly of said frame, and clips secured to said strips at spaced apart locations therealong, said backing plate having slots therein disposed one adjacent each of said clips and each of said clips comprising a main body portion disposed at the frame adjacent side of the corresponding strip and secured to the latter, a flange directed outwardly from said body portion at one end thereof and secured to the bead of the corresponding strip, and a tab extending from the same end of said main body portion through the adjacent slot in said backing plate and disposed against the side of said backing plate remote from the strip.
